CLAIM

The ornamental design for a wall mount for exercise rack, as shown and described.

DESCRIPTION

FIG. 1 is a top, front, right perspective view of a wall mount for exercise rack showing my new design;

FIG. 2 is a top, front, left perspective view thereof;

FIG. 3 is a top view thereof;

FIG. 4 is a cross-sectional view thereof at 4-4 in FIG. 2;

FIG. 5 is a right side view thereof;

FIG. 6 is a left side view thereof;

FIG. 7 is a front view thereof; and,

FIG. 8 is a bottom, front, right perspective view thereof. The broken lines immediately adjacent to the shaded area are directed to boundary lines which form no part of the claimed design. The broken lines in the drawings are for the purpose of illustrating portions of the wall mount for exercise rack and form no part of the claimed design.
